UNITED STATES PATENT OFFICE.

ALPHONSINE JOSEPHINE CLAVELOUX, OF SAN FRANCISCO, CALIFORNIA.

DESIGN FOR A CORSET.

SPECIFICATION forming part of Design No. 26,044, dated September 15, 1896.

Application filed November 20, 1895. Serial No. 569,584. Term of patent 14 years.

To all whom it may concern:

Be it known that I, ALPHONSINE JOSEPHINE CLAVELOUX, a citizen of the United States, residing at San Francisco, in the county of San Francisco and State of California, have invented and produced a new, useful, and original Design for Corsets, of which the following is a specification, reference being had to the accompanying drawing, forming a part thereof.

My invention relates to designs for corsets; and it consists in the shape and configuration which will be more fully described herein-after.

15 The accompanying drawing represents a plan view of a half of a corset which embodies my invention.

The leading or characteristic feature of my design consists of the outline configuration 20 thereof, comprising the inwardly-curved rear edges, the upper edge rising at a sharp angle from the top of the rear opening of the corset to the straight under-arm portion of the upper edge, which, at a point directly forward of the armpit portion, sharply falls to a point below the wearer's breast, and thence continues in a substantially straight line to the top of the front opening, substantially as shown.

A represents one-half of a corset which 30 has its rear edge B curved inwardly and provided with a series of lacing-holes C. The top rear edge or corner D of each half of the corset where it fits in between the shoulder-blades is rounded or cut away, and from this 35 rounded or cut-away portion the edge F extends on a substantially straight line to a point G in front of the armpits, and from this point the edge at H is cut away, so as to make an abrupt descent to the point I to one side 40 of the breast. From the point I the top edge forms substantially a straight line, as shown at P, where it extends across under the breast. The front edge J of each half of the corset forms a straight line, while the lower 45 edge is formed on a curved line O, about as shown.

Having thus described my invention, I claim—

The design for a corset, substantially as 50 shown and described.

In testimony whereof I affix my signature in presence of two witnesses.

A. JOSEPHINE CLAVELOUX.
